UNITED STATES PATENT OFFICE.

ALEXANDER STROBL, OF NEW YORK, N. Y.

DESIGN FOR A SELF-LUMINOUS LOCATOR FOR LIGHTING FIXTURE OR SIMILAR ARTICLE.

Application filed April 4, 1922. Serial No. 1,529. Term of patent 3½ years.

To all whom it may concern:

Be it known that I, ALEXANDER STROBL, a citizen of Hungary, residing at New York, county and State of New York, have invented a new, original, and ornamental Design for Self-Luminous Locator for Lighting Fixtures or Similar Articles, of which the following is a specification, reference being had to the accompanying drawing, forming part thereof.

The figure is a front elevational view of a self-luminous locator for lighting fixtures, or similar articles.

What I claim is:—

The ornamental design for a self-luminous locator for lighting fixtures or similar articles, as shown.

ALEXANDER STROBL.
